ROBERT J. PETERSON, OF MOUNT VERNON, NEW YORK.

DESIGN FOR FABRIC.

SPECIFICATION forming part of Design No. 29,605, dated November 1, 1898.

Application filed May 20, 1898. Serial No. 681,262. Term of patent 14 years.

To all whom it may concern:

Be it known that I, ROBERT J. PETERSON, a citizen of the United States, residing at Mount Vernon, county of Westchester, and 5 State of New York, have invented and produced a certain new and original Design for a Fabric or Similar Article, of which the following is a specification.

My invention resides in the design for a fabric or similar article.

The design consists substantially in a series of straight-line bars 1 2, printed or woven in the fabric, the bars extending across the fabric diagonally to the direction of the length 15 of the piece. Said bars contrasting in color

and being separated leave white or uncolored spaces or bars 3, parallel with the others, and upon the white spaces lying between the colored bars are produced stars 4 of a color contrasting with the bars 3.

Having described my invention, I claim—

The design for a fabric, or similar article, substantially as herein shown and described.

Signed in the city, county, and State of New York this 19th day of May, 1898.

ROBERT J. PETERSON.
